UNITED STATES PATENT OFFICE

2,001,832

AIR CONDITIONER

Walter Bandurski, Chicago, Ill.

Application August 29, 1934, Serial No. 741,968

12 Claims. (Cl. 257—244)

My invention relates to improvements in gaseous fluid conditioners of the type adapted to either heat or cool air or other gaseous fluid prior to its being used.

5 An object of my invention is to provide an improved type of gaseous fluid conditioner.

A further object is to provide such a conditioner which will cool or heat the fluid quicker than will the present types of conditioners.

10 A further object is to provide a device of this character in which the heating or cooling units are arranged in a cone shape helical coil.

A further object is to provide such a device which is strong and sturdy in structure yet can 15 be quickly and cheaply constructed by one skilled in the art.

Other objects and advantages reside in the particular structure of my device, combination and arrangement of various parts and in the 20 mode of operation,—all of which will be readily understandable to those skilled in the art upon reference to the drawing and detailed description forming a part of this specification.

In the drawing:

25 Figure 1 is a vertical longitudinal section through a preferred form of my device.

Figure 2 is a vertical cross section taken on the line 2—2 of Fig. 1, and

Figure 3 is a fragmentary view of the forward 30 end of the device.

With further reference to the drawing, wherein like reference characters have been used throughout to designate like parts, 5 is a hollow cylindrical casing having a beaded forward edge 6.

35 The forward edge 6 has also an inwardly extending flange 7 which prevents moisture from flowing out of the casing 5 at this end. While my preferred form of casing is cylindrical, it is to be understood that it could also be oval or even 40 angular in cross section.

A series of zig-zag or otherwise formed supports 8 extend radially and inwardly from the forward edge of the casing 5 and may have their outer ends secured within the bead 6, as clearly 45 shown in Fig. 1, or they may be secured to the casing in any other suitable manner. The inner ends of the supports 8 are secured to and support the forward edge of a cone-shaped baffle B in any suitable manner. As is readily seen, the 50 apex of the baffle B is within the casing 5 and is supported by a member 14 carried by the casing or it may be supported in any other suitable manner.

At the rear or inlet end of the casing 5 is a 55 wall 9 having a plurality of openings 9a therein

and also an opening S' centrally thereof. A motor M is carried by the wall 9 in any suitable manner and the shaft S of the motor extends into the casing 5 through the central opening S'. A fan F is mounted on the inner end of the shaft and is formed for drawing air into the casing 5 through the openings 9a in wall 9 and expelling it around the enlarged forward edge of the baffle B. Of course, any suitable blower could be substituted for the one shown and it could be carried 10 at the forward end of the casing instead of at the rear. In the event that the wall 9 is eliminated, as may well be the case, a flange (not shown) similar to the flange 7 for the forward edge may be substituted and the motor may be supported 15 by a suitable spider.

A layer of felt or other insulating material 10 may be attached to the inside periphery of the casing and it will be noted that the lower longitudinal edges 10a and 10b of the material 10 are 20 spaced apart at the bottom of the casing to provide a channel 11. Thus, any moisture that may drip down from the baffle, coil or walls will be readily drained away through the drain 12 in the rear of the channel 11. To facilitate draining, the 25 forward floor of the channel 11 may be slightly higher than the rear floor. A closure 13 is provided for the drain 12 but it is obvious that suitable plumbing connections could be substituted.

Heating or cooling of the air blown through the 30 casing is accomplished by the cone-shaped helical coil 19 through which the heating or cooling fluid is circulated by any suitable means (not shown). It will be observed that the coil 19 is centrally supported in the casing 5 by offset portions 14a 35 and 14b of the member 14. Of course, other supporting means could be substituted, however.

It is realized that it is old to heat or cool air by passing it over a coil containing a heating or cooling fluid. However, by arranging my coil in 40 a cone-shape with the apex toward the fan, I have found that the air stream is much more thoroughly subjected to the action of the coils and that, consequently, fewer convolutions are necessary and the room or building is heated or cooled in a much quicker time. Hence, power is 45 saved and a more economical device is achieved. My device acts on the air quicker because all the air drawn into the casing does not pass over the same convolutions, (see Fig. 2) there are but minute ring-shaped openings through my casing from the front to rear and that substantially all the air is subjected to direct contact to at least one convolution of the coil 19. Then too, the 50 cone-shaped baffle will act to deflect the more cen-

tral parts of the air stream outwardly so that all portions of the stream pass on out of the casing in a more compact diverging annular stream.

By using a cone-shaped baffle, I am able to 5 eject the air from my casing in a stream that is continuously diverging in all directions which results in the room or building being more quickly cooled or heated and also minimizes drafts. However, beneficial results have been obtained when 10 the baffle is entirely eliminated.

The bulk of the air which enters the casing is deflected outwardly from the center of the casing by the baffle B. However, it is apparent from Figure 1 that the extreme outer portion of the 15 air stream is deflected outwardly by the deflected inner portion at a point adjacent the restricted outlet of the casing and that the entire stream emerges from the casing in the form of a constantly diverging annular stream.

20 By means of the baffle, none of the air ever gets very far from the convolutions while it is within the casing but by having the convolutions tapered to conform to the shape of the baffle, I am able to bring the air even closer to the coil 25 throughout its course.

It is readily understandable that many changes can be made in my device without departing from the spirit of the invention. For instance, the baffle and coil cones might be oval in section, 30 or square, or polygonal or other changes in the form or structure might be made.

It is to be understood, therefore, that I do not limit myself to the precise form of casing, baffle and coil and that the drawing and description are 35 illustrative rather than limitative.

Having thus described my invention,

I claim:

1. An air conditioner comprising a casing, an 40 apertured end wall in said casing, a fan and motor carried by said wall for forcing a stream of air through said casing, a cone-shaped baffle axially carried within said casing and having its apex disposed toward said end wall, and air conditioning means for said air stream arranged within 45 in said casing in the form of a substantially cone-shaped coil.

2. An air conditioner comprising a casing, an 50 apertured end wall in said casing, a fan and motor carried by said wall for forcing a stream of air through said casing, a cone-shaped baffle axially carried within said casing and having its apex disposed toward said end wall, and air conditioning means for said air stream arranged within 55 in said casing in the form of a substantially cone-shaped coil arranged concentrically about and spaced from said baffle.

3. An air conditioner comprising a casing, an 60 apertured end wall in said casing, a fan and motor carried by said wall for forcing a stream of air through said casing, a cone-shaped baffle axially carried within said casing and having its apex disposed toward said end wall, and air conditioning means for said air stream, said means comprising a fluid conduit arranged in a tapered 65 helical coil.

4. An air conditioner comprising a casing, an 70 apertured end wall in said casing, a fan and motor carried by said wall for forcing a stream of air through said casing, a cone-shaped baffle axially carried within said casing and having its apex disposed toward said end wall, and air conditioning means for said air stream, said means comprising a fluid conduit arranged in a tapered 75 helical coil having the smallest convolutions thereof disposed toward said end wall.

5. An air conditioner comprising a casing, an apertured end wall in said casing, a fan and motor carried by said wall for forcing a stream of air through said casing, a cone-shaped baffle axially carried within said casing and having its apex disposed toward said end wall, and air conditioning means for said air stream, said means comprising a fluid conduit arranged in a tapered helical coil arranged concentrically about and spaced from said baffle. 5

6. An air conditioner comprising a hollow casing, an air inlet at one end of said casing and an air outlet at the other, means carried by one end of said casing for causing a stream of air to pass therethrough, a tapered baffle axially disposed within said casing and having its apex disposed towards said inlet end, and air conditioning means within said casing comprising a fluid conduit comprising a tapered helical coil 15 concentrically arranged about said baffle and spaced therefrom. 20

7. An air conditioner comprising a hollow casing, an air inlet at one end of said casing and an air outlet at the other, means carried by one end of said casing for causing a stream of air to pass therethrough, a cone-shaped baffle axially disposed within said casing and having its apex disposed towards said inlet end, and air conditioning means within said casing comprising a fluid conduit comprising a tapered helical coil 25 concentrically arranged about said baffle and spaced therefrom. 30

8. An air conditioner comprising a hollow casing having an air inlet at one end and an air outlet at the other end, means carried by said 35 inlet end for forcing a stream of air through said casing, a baffle axially disposed in said casing for diverging said air stream in all directions at said outlet, and air conditioning means within said casing comprising a fluid conducting conduit arranged in the form of a tapered helical coil. 40

9. An air conditioner comprising a hollow casing having an air inlet at one end and an air outlet at the other end, means carried by said 45 inlet end for forcing a stream of air through said casing, a baffle axially disposed in said casing for diverging said air stream in all directions at said outlet, and air conditioning means within said 50 casing comprising a fluid conducting conduit arranged in the form of a tapered helical coil having the smallest convolutions thereof disposed towards said inlet end.

10. An air conditioner comprising a hollow casing, an air inlet at one end of said casing and an air outlet at the other, means carried by one 55 end of said casing for causing a stream of air to pass therethrough, and air conditioning means within said casing comprising a fluid conducting conduit arranged in the form of a tapered helical coil. 60

11. An air conditioner comprising a hollow casing, an air inlet at one end of said casing and an air outlet at the other, means carried by one end of said casing for causing a stream of air to pass therethrough, and air conditioning means 65 within said casing comprising a fluid conducting conduit arranged in the form of a tapered helical coil having the smallest convolutions thereof disposed toward said inlet end.

12. An air conditioner comprising a hollow cylindrical casing, an end wall providing air inlets at one end of said casing, blower means carried by said end wall for forcing a stream of air through said casing, a layer of insulating material extending around the greater part of the inner 70 75

walls of said casing but having its lower edges spaced apart to provide a longitudinally extending channel along the bottom of said casing a drain at one end of said channel, a cone-shaped baffle carried by the open end of said casing and having its apex disposed towards and axially of

said end wall, and air conditioning means within said casing comprising a fluid conducting conduit in the form of a substantially cone-shaped helical coil concentrically arranged about said baffle and spaced therefrom.

WALTER BANDURSKI.
